LINE SUPPORTING DEVICE

Arthur A. Ensminger, Cleveland, Ohio, assignor
to R & E Appliance Company, Cleveland, Ohio,
a corporation of Ohio

Application January 13, 1948, Serial No. 2,098

7 Claims. (Cl. 211—119.16)

1

This invention relates to line supporting devices, more particularly to supports of the overhead type for mounting a multiplicity of clothes lines.

It is necessary, during inclement weather, for washing to be hung indoors for drying. Most homes do not have separate laundry or drying rooms that are of sufficient size and that can be set aside exclusively for the purpose of drying clothes. Accordingly, it is customary for clothes lines to be strung in basements and recreation rooms. When the same space is to be used for other purposes the presence of clothes lines strung across the area presents a problem because of the inconvenience and hazard involved. Furthermore, permanent line supports installed at heights convenient to the reach of the housewife are in the way and present hazards even though the lines may be removed or taken down between periods of use.

It is therefore one of the principal objects of the present invention to provide a generally improved line supporting device of simple and inexpensive construction which may be permanently attached in place and which incorporates an elongated member or rod to which lines may be attached, the elongated rod being bodily shiftable laterally for adjustment to different positions for use and for storage. More specifically, the invention conceives a line supporting device for overhead mounting as by attachment to a ceiling joist in a basement or recreation room, the device including a swinging arm which mounts an elongated rod or bar that is swung bodily and laterally in an arc to different positions.

Another object is to provide line supporting devices of the swinging or pivoting arm type in which the arms have relatively wide ends which mount elongated bars or rods to which the lines are attached, the devices being used in pairs with the bars disposed in parallel relation so that by pivoting the arms upwardly in unison, the lines can be moved upwardly, providing head clearance in the room in which the lines are suspended.

Another object is to provide a swinging arm type line support in which is incorporated improved means for retaining the arm in different angular positions so that the lines may be adjusted as to tension or height.

A further object of the invention is to provide a line support in which an elongated bar or rod is supported horizontally in the lower end of a swinging arm, the rod being movable bodily laterally during swinging of the arm and the rod also being relatively rotatable in the arm as the

2

latter is swung to different positions of adjustment, thereby maintaining a predetermined relative orientation between the rod and the lines attached thereto.

Still further objects of the invention relate to certain details of construction and arrangements of parts which will become apparent from the following detailed description. This description is made in connection with the accompanying drawings forming part of the specification and in which like parts throughout the several views are indicated by the same letters and numerals of references.

In the drawings:

Fig. 1 is a side elevational view, foreshortened and somewhat diagrammatic, showing a pair of line supporting devices embodying the principles of the present invention attached as to a basement ceiling joist and supporting a number of runs of flexible clothes line or rope;

Fig. 2 is a horizontal view, partially in section and with parts broken away and removed, showing the plan form of the line supporting arrangement of Fig. 1, this view being taken substantially on the line indicated at 2—2 of Fig. 1 and enlarged with respect to that figure;

Fig. 3 is an elevational view, partly in section and with parts broken away and removed, of one of the line supporting devices, this view being enlarged with respect to the preceding views;

Fig. 4 is a fragmentary elevational detail, with parts broken away and removed, showing the mounting bracket;

Fig. 5 is a horizontal sectional detail through the mounting bracket taken substantially on the line indicated at 5—5 of Fig. 3, this view also showing in broken lines alternative positions of the floor joist to which the bracket is attached; and

Fig. 6 is an elevational view of one of the figure 3 line fasteners of bent metal rod or wire, this view being drawn to substantially the same scale as Fig. 3.

A representative basement installation utilizing the line supporting devices of the present invention is illustrated and includes brackets A secured in spaced apart relation to the underside of joist B of the floor above and carrying pivoted arms C in hanging or suspended relation. On the lower ends of the arm C a pair of cantilever rods or bars D are mounted horizontally in spaced parallel relation, clothes line E being strung between the bars D in a number of parallel runs.

Each of the brackets A comprises a metal base

plate or member 2 which is formed with a plu-

rality of apertures 3 that receive attaching means such as bolts or lag screws 4. The bracket base plate 2 is disposed flatwise against the bottom edge face of the wooden floor joist B and the lag screws 4 are screwed into the latter, suitable guide holes being first drilled in the desired locations. In Fig. 1 the brackets of the two line supporting devices are shown attached to the same floor joist, the brackets being disposed in relation to the floor joist as indicated in Fig. 3 and by the full lines in Fig. 5. Should it be desired to locate the line supporting devices in other relative positions, as, for example, on different joists, the base plate of each of the brackets may be disposed against the underside of the joist in the relative position indicated by the broken lines of Fig. 5. Other methods of attaching the bracket base plates to the ceiling of a room may be used, as will be apparent to persons familiar with such matters.

Extending downwardly from the base plates 2 and rigid therewith are spaced parallel guide elements 5 and 6 which closely embrace the pivoted arms C and support the latter as by a pin or through bolt 7 which passes through aligned openings in the guide elements 5 and 6 and in the swinging arms. The guide elements of each bracket are desirably the spaced parallel sides or flanges of a channel shaped metal stamping of substantially U form in cross section, the sides being integrally connected by channel bottom or web 10 which also serves as a stop for the swinging arm.

Suitable means is provided for locking or retaining each of the swinging arms in different positions of angularity with respect to the horizontal and to its supporting bracket. A preferential arrangement utilizes a wing bolt 8 threaded through an aperture in the lower portion of the guide element 5, the latter being reinforced as by an integral or welded-on boss 9 in the region of the threaded hole that receives the wing bolt. By tightening the wing bolt 8 so that the latter bears against one side of the swinging arm C, the arm is clamped between the end of the wing bolt and the inside face of the guide element 6.

In locating the openings for the support bolt 7 and the threaded aperture for the wing bolt 8, full advantage is taken of the dimensional characteristics of the bracket and the arm to space the support bolt and the clamping wing bolt as far apart as possible while yet keeping the side face of the arm C in position to be engaged by the end of the wing bolt in all positions of adjustment. A suitable arrangement is one such as that illustrated in which the support bolt 7 is above the clamping wing bolt, the support bolt being disposed adjacent the open side of the channel bracket and the wing bolt 8 being disposed adjacent the web or closed side of the bracket.

The upper end of the swinging arm C, curved or rounded as indicated at 19 to clear the bracket web 10, is relatively thin or narrow in the direction of the pivot axis so as to be received between and guided by the inside surfaces of the guide elements 5 and 6 of the channel brackets. The bottom or lower end of the swinging arm is relatively wide, however, to supportingly receive spaced parts of a central portion of the elongated bar or rod D. Although the swinging arm may be machined from solid stock or formed as a casting, it has been found to be very economical to make the arm of a pair of flat iron or steel strips 14 and 15. The upper portions of the two

strips or arm members, disposed flatwise against one another and secured together as by welding, are received between the guide elements 5 and 6 of the support brackets and pivoted as a unit on the bolt 7 as previously described.

Lower portions 16 of the strips 14 and 15 are divergently disposed, providing a relatively wide bifurcated lower end on the arm. Endmost portions 17 of the arm pieces or strips 14 and 15 are angularly disposed with respect to the divergent portions 16 and are substantially parallel to one another. These endmost portions are formed as with circular apertures, one of which is indicated at 18, to receive the horizontal bars or rods D. Thus, the rods are contacted at relatively widely spaced points or regions by the lower or wide end of the generally Y shaped swinging arm so as strongly to resist twisting of the rod relative to the arm.

The rod or bar D may be solid metal or wood although preferably it is of tubular form, conventional metal pipe being suitable. At spaced intervals along the length of the rod, means such as figure 8 fasteners 20, bent from steel wire or bar stock, are provided for attaching the rope lines 1. One loop of each of the bent fasteners 20 is received in embracing relation about the rod D, the latter preferably being formed as by cutting, or, preferably, by pressure rolling with a rotary tool or wheel, at spaced intervals along its length with annular channels or grooves 21 which receive the fastener loops interlockingly to prevent sliding of the fasteners along the rod.

The fasteners are first sprung to enlarge their loops or eyes so that they can be threaded axially onto the rod D and are then clinched in place in the circumferential grooves 21, clearance being maintained to permit rotary movement or adjustment of the fasteners on the rod. The other loops of the fasteners 20 receive the lines 1 to be supported by the device. The rod D is freely slidable axially in the arm apertures 18, the sliding movement being limited by engagement of the innermost pair of the fasteners 20 against the outside faces of the endmost portions 17 of the Y shaped arm. This sliding fit of the line supporting rod in the lower ends of the swinging arm eliminates any necessity for precise adjustment of the parts and permits the device to be shipped and handled in knocked-down condition. The rod D is formed in two parts of equal length having their inner ends externally threaded to receive a conventional pipe coupling 22. This coupling may be used to limit axial sliding of the rod in the arm should it be desired to omit the central line fasteners. The user assembles the device on the site by inserting the rod parts through the openings 18 in the swinging arm and screwing the threaded rod ends into the coupling 22. The rod is prevented from sliding out of the swinging arm while yet being rotatable therein to different positions of adjustment and axially slidable over a limited path.

Although a series of clothes lines may be strung using but one of the line supporting devices, the other ends of the lines being attached to a wall or other support, it is preferable to employ a plurality of the line supports as shown in Figs. 1 and 2. When a pair of the supports are thus used the clothes line 1 may be cut into equal lengths, the ends of which are tied to corresponding loop fasteners on the spaced rods D or, as shown, a single length of the clothes line may be strung back and forth loosely through the eyes or loops of the fasteners 20 in a series of parallel

runs, the ends only of the line being tied to the fastener loops.

The arms C are locked in their lower positions, indicated by the full lines of the figures, by tightening the wing bolts 8 thereagainst. When not in use the lines may be raised out of the way to provide head room by swinging the arms C upwardly in unison to the broken line positions indicated in the drawings. The arms C and the line carrying rods D are secured in the raised positions shown by tightening the wing bolts 8 against the arms. By stringing the lines 1 under tension the arms C will tend to remain in raised positions without using the clamping screws or bolts 8 simply by swinging the left arm, as viewed in Fig. 1, upwardly beyond "dead center" position. Height adjustment to suit the convenience of the individual user is obtained by moving the arms C to positions intermediate those shown, in each instance the arms being locked in the desired adjusted positions by means of the wing bolts 8.

In addition to using the line supporting devices in pairs or tandem as illustrated, they may also be employed in greater number, the brackets A being aligned and the lines 1 being threaded through the loop fasteners 20 of the intermediate supports, thus eliminating the need for clothes props on long suspensions. When so employed the fasteners 20 of the central supports are rotated so as to extend downwardly.

In their lowermost positions the arms C engage the channel webs 10 of the brackets, limiting the movement of the arms. Thus, in the arrangement shown in Fig. 1, only the locking wing bolt 8 of the right hand support need be tightened against the swinging arm, the arm C of the left hand support bearing against the channel web 10. When using a series or multiplicity of line supports this feature is particularly advantageous since the lines can be held in lowered or utility position by locking only the endmost swinging arm.

The line supporting device is in the general form of an inverted T structure, the base of the T being secured against the underside of the ceiling or joist and the cross member or arm of the T being swingable bodily and laterally in tightening the lines and in moving the lines to an out-of-the-way position when not in use. The ends of the cross member or rod D are thus supported cantilever fashion by the relatively wide lower end of the swinging arm. Contacting of the rod at relatively widely spaced points by the swinging arm provides a strong joint or connection which is effective in resisting twisting of the rod on the arm under conditions of unbalanced loads which frequently occurs in hanging clothes on the lines.

In accordance with the provisions of the patent statutes the principles of the present invention may be utilized in various ways, modifications and alterations being contemplated, substitution of parts and changes in construction being resorted to as desired, it being understood that the embodiment shown in the drawings and described above is given merely for purposes of explanation and illustration without intending to limit the scope of the claims to the specific details disclosed.

What I claim is:

1. In a line supporting device, bracket means for attachment to an overhead support, an arm depending from the bracket means and having a transverse opening therethrough, an elongated

bar extending through the opening in the arm and rotatable therein, the bar also being axially movable in the arm opening, spaced means on the bar and located on opposite sides of the arm for attaching lines to the bar, said line attaching means also serving to limit the axial movement of the bar in the arm, the arm being pivoted on the bracket means for swinging movement about a substantially horizontal axis and thereby movable relative to the bracket means for shifting the bar bodily laterally in line tensioning and positioning adjustments in which the rod is substantially free to turn in the arm, and means for holding the arm in different positions of adjustment relative to the bracket means.

2. In a line supporting device, bracket means for attachment to an overhead support, an arm depending from the bracket means and pivoted thereto for swinging movement, the arm having a transverse opening therethrough, an elongated bar extending through the arm opening and forming with the arm an inverted T structure, means on the bar on opposite sides of the arm for attaching lines thereto and for limiting axial shifting movement of the bar in the arm opening, the longitudinal axis of the bar being substantially parallel to the pivot axis of the arm whereby the bar is swingable in an arc bodily laterally in line positioning and tightening adjustments of the T structure, and means for holding the arm in fixed adjusted positions relative to the bracket means.

3. In a line supporting device, bracket means for attachment to an overhead support, an arm depending from the bracket means and pivoted thereto for swinging movement, the arm having a transverse opening therethrough, an elongated bar extending through the arm opening and forming with the arm an inverted T structure, means on the bar on opposite sides of the arm for attaching lines thereto and for limiting axial shifting movement of the bar in the arm opening, the longitudinal axis of the bar being substantially parallel to the pivot axis of the arm whereby the bar is swingable in an arc bodily laterally in line positioning and tightening adjustments of the T structure, and screw means for effecting a frictional interlock between the arm and the bracket means for holding the device with the T structure in different positions of adjustment.

4. In a line supporting device, an arm and means on one end thereof for attaching the same to a support, the other end of the arm having spaced parts with aligned apertures therethrough, a multiple part rod extending through the arm apertures, coupling means disposed between the spaced arm parts and secured to adjacent ends of the rod parts to retain the latter in alignment, the rod being formed with a series of circular grooves spaced along the length thereof, and fasteners for attaching lines to the rod, said fasteners each including a loop embracing the rod and disposed in one of the grooves to prevent shifting of the fasteners axially along the rod.

5. In a line supporting device, an arm and means on one end thereof for attaching the same to a support, the other end of the arm having spaced parts with aligned apertures therethrough, a multiple part rod extending through the arm apertures, the rod being formed with a series of circular grooves spaced along the length thereof, and fasteners for attaching lines to the rod, said fasteners each including a loop embracing

the rod and disposed in one of the grooves to prevent shifting of the fasteners axially along the rod, one pair of the fasteners being disposed one on each side of the spaced arm parts and closely adjacent thereto to serve as limiting stops for engagement with the arm parts to restrict axial movement of the rod in the arm apertures.

6. In a line supporting device, an arm and means on one end thereof for attaching the same to a support, the other end of the arm having spaced parts with aligned apertures therethrough, an elongated rod extending through the arm apertures, the arm engaging a central portion of the rod so that the ends of the rod project from the arm cantilever fashion, the rod being formed with a series of circular grooves spaced along the length thereof, and fasteners for attaching lines to the rod, said fasteners each including a loop embracing the rod and disposed in one of the grooves to prevent shifting of the fasteners axially along the rod.

7. In a line supporting device, an arm and means on one end thereof for attaching the same to a support, the other end of the arm having spaced parts with aligned apertures therethrough, an elongated rod extending through the arm apertures, the arm engaging a central portion of the rod so that the ends of the rod project from the arm cantilever fashion, the rod being formed with a series of circular grooves spaced

5
10
15

along the length thereof, and fasteners for attaching lines to the rod, said fasteners each including a loop embracing the rod and disposed in one of the grooves to prevent shifting of the fasteners axially along the rod, one pair of the fasteners being disposed one on each side of the spaced arm parts and closely adjacent thereto to serve as limiting stops for engagement with the arm parts to restrict axial movement of the rod in the arm apertures.
